RANGE

Lawrence A. Althoff, Chicago, Ill.

Application July 21, 1932, Serial No. 623,873

5 Claims. (Cl. 126—36)

This invention relates particularly to ranges. The invention is illustrated in connection with a coal-gas combination range but various features thereof may be employed with either type of range separately and with other kinds of ranges.

A primary object of the invention is to provide an improved and simplified range construction and in which various features of improvement are embodied. These features include a reinforced frame construction in which the sides of the range support freely the top burners and top plates of the range, thus dispensing with the frame top heretofore in use, an improved frame construction in which the side walls are provided with conformations which buttress the walls and take the place of posts or beams, an improved circulation passage for discharged gases by which the heat therein is utilized, a heating conduit by which fresh air is caused to pass through the range in contact with heated surfaces, and an oven outlet flue by which vapors in the oven may be carried to the main outlet flue. Other objects and advantages will appear as the specification proceeds.

The invention is described, in its preferred embodiment, in the accompanying drawings, in which:

Figure 1 is a view in elevation of a range embodying my invention, the range being equipped with a cover, preferably of the foldable type; Fig. 2, a broken plan view; Fig. 3, an enlarged vertical sectional view, the section being taken as indicated at line 3 of Fig. 2; Fig. 4, a plan sectional view, the section being taken as indicated at line 4 of Fig. 3; Fig. 5, a broken enlarged sectional view, the section being taken as indicated at line 5 of Fig. 4; Fig. 6, a broken side view; Fig. 7, an enlarged sectional detail view, the section being taken as indicated at line 7 of Fig. 1; Fig. 8, an enlarged detail sectional view, the section being taken as indicated at line 8 of Fig. 2; and Fig. 9, a view similar to Fig. 8, showing a modified form of the invention.

In the illustration given, A designates the coal burning compartment of the range, B, the gas burning compartment of the range, and C, a heating conduit disposed between compartments A and B.

The walls of the range are preferably so constructed as to dispense with the need for reinforcing vertical posts and horizontal beams. In the illustration given, the front side 10 is preferably formed of a single casting having openings therein in which the doors may be fitted and openings for the burner handles, etc. The edges 11 of the front side 10, in the casting operation, are formed so as to present a rolled or semi-tubular appearance. The rolled edges 11 thus form vertical hollow posts as well as horizontal hollow beams which give to the plate 10 all the

strength formerly supplied by separate posts and beams. In addition, the rolled edges, projecting as they do beyond the plane of the body of the plate, protect the plate not only from blows but also, to a considerable extent, from contact with objects which would tend to soil or disfigure the body of the plate.

The sides 12 and 13 may also be formed from a single casting. I prefer, however, for the purpose of economy in manufacture, to form the sides in two castings provided with overlapping joints 14. The sides 12 and 13 are also provided with rolled edges 11. However, as shown more clearly in Fig. 6, the front rolled edge is preferably cut away at 15 so as to provide a straight edge adapted to abut and form a tight joint with the rear side of the rolled edge 11 of the front side 10. The front side 10 and the side walls 12 and 13 may be secured together by any suitable means. As shown in Fig. 7, the walls may be provided with integral lugs 16 and 17 which are brought into overlapping relation and secured together by means of screws 18 extending through a perforation in one flange and engaging a threaded recess in the other flange. Any suitable fastening means may, however, be employed.

My improved range top is formed in such a way as to dispense with the top frame formerly employed, while at the same time permitting the top burner elements and plates to be readily removed or replaced. This is accomplished by equipping the rolled edges 11 with lugs or flanges 19. By employing the tubular edges, the lugs 19 may extend well into the hollow body and be rigidly and securely bound thereto. Preferably, the lugs or flanges 19 are formed integrally with the sides 12 and 13 and the front 10 and because of the extensive attachment surface between the lugs 19 and the hollow border members 11, there is little danger of the breaking of the lugs when the top elements are dropped thereon. The flanges or lugs 19 are equipped with projections 20 upon which the burner plates 21 may rest. Across the coal burning compartment A I prefer to employ a pair of cross strips 22 and 23 which rest upon the front and rear walls of the range and which are provided with lateral flanges 24 adapted to support the burner plate 25 as well as one side of the gas burner top 21. With this construction, the burner tops 21 and the coal range top 25 may be readily lifted off of the supporting flanges and lugs so as to expose the entire range surface therebelow. Likewise, these parts may be replaced without the necessity of using bolts, screws and other like means.

The back wall of the range may be of any suitable shape and material. In the illustration given more clearly in Figs. 3, 4 and 5, the back wall includes at the top a casting strip 26 which

is provided with a longitudinal channel 27. The channel is covered by back sheet 28 thus providing a closed horizontal passage which communicates at one end with the flue outlet 29. 5 Centrally disposed within the channel 27 is a vertical channel or passage 30. As shown more clearly in Fig. 5, the passage 30 extends downwardly and communicates through opening 31 with the upper lining 32 of the oven. The 10 upper lining 32 is perforated at 33 to permit vapors from the oven to pass through the upper lining and channel 30 into the horizontal passage leading to the outlet flue 29. Below the back strip 28 is another back strip or sheet 34 15 which forms the remainder of the rear wall for the gas range compartment B. A cast plate 35 closes the rear side of compartment A, as shown more clearly in Fig. 6.

The coal burning compartment A is provided 20 with a fire box 36 which may be of any suitable construction. Below the fire box is supported an ash pot 37. Below the floor 38 which supports the ash pot 37 is a second floor 39 which is spaced from floor 38 and provides therebetween a circulation chamber. A partition 40, 25 which extends from the rear wall but terminates short of the front wall, divides the compartment into two communicating passages 41 and 42. The passage 41 communicates at its rear with a vertical passage 43 which opens 30 just above the fire box 36. A similar rear passage 44 leading from the flue outlet 29, communicates with flow passage 42. A by-pass opening or aperture 45 establishes communication 35 between the upper portion of passage 44 and the fire place. This aperture is controlled by a damper 46, the handle 47 of which extends through the side 13. When the damper is closed, the hot gases from the fire box are 40 compelled to pass through the vertical passage 43 to the horizontal passage 41 below the fire box, and after having passed to the front of the passage are returned by passages 42 and 45 to the outlet flue 29. This circulation of the heated gases serves to heat up the metal 45 of the range walls which in turn radiate heat to the room and particularly radiate heat to the fresh air passing through the heating channel C which will be described more in detail hereinafter. 50

The gas burner compartment B may be of any suitable construction. In the illustration given, the upper part of the chamber affords a space for the burners 48. The major portion of the 55 compartment is occupied by the oven compartment 49. The oven may be of any suitable construction. As illustrated, it is shown provided with the top insulation wall 32 and the side insulation walls 50 and 51.

60 The heating channel C is formed by the spacing apart of the insulation wall 51 and the coal burner wall 52. Each end of the channel is left open so that air may pass freely from beneath the range past the heated metal 52 of the coal burner wall and the air thus heated in the channel C escapes through the openings of the burner top 21.

A drip pan 53 is preferably supported upon the top lining 32 and below burners 48.

70 The operation of the range is apparent from the foregoing description.

In starting a fire in fire box 36, it is preferred to leave the damper 46 open until the fire is under way. The damper is then closed and the heated gases caused to circulate through the conduits 43, 41, 42 and 44. The circulation of the hot gases not only permits further combustion in the passages but also heats up the metal of the range and particularly the inner wall 52 which is adjacent the heating channel C. When it is desired to have access to the top portions of the range, the burner tops 21 and the burner plate 25 may be lifted off the flanges and lugs 19 and 24. To again form the cooking top for the range, it is only necessary to replace the burner plate 25 and the burner tops 20. 15

In the modified form of border shown in Fig. 9, the edge instead of being rolled is formed in the shape of a rectangle or square 11^a. Extending through the open side of the square is the supporting lug 19^a which is firmly secured to 20 the inner side of member 11^a. The lug is provided with a projection 20^a adapted to carry the burner top.

The foregoing detailed description has been given for clearness of understanding only and 25 no unnecessary limitations should be understood therefrom, but the appended claims should be construed as broadly as permissible, in view of the prior art.

I claim:

1. A range comprising front, rear and side walls, at least one of the walls having its top portion turned forward and back to form a hollow reinforcing rim open at its rear side, supporting brackets secured within said hollow rim 35 and extending inwardly, and a burner top resting upon said supporting brackets.

2. A range comprising front, rear and side walls, the front and side walls having their border portions turned back to form vertical 40 and horizontal reinforcements, and means carried within the top hollow portions of said sides for supporting thereon a burner top.

3. A range comprising front, rear and side walls formed of cast iron, the front and side 45 walls having their top edge portions forming tubular borders, said borders and the top of said rear wall being provided with supporting ledges, and a separable range top, comprising a burner plate and gas burner tops, resting freely upon said ledges.

4. A coal-gas range comprising front, rear and side walls, said front and side walls having their top edge portions forming tubular portions open at their rear sides, supporting brackets secured within said tubular portions and having inwardly extending ledges, said rear plate also being provided with a supporting flange, a coal-burner box, a burner plate supported thereabove upon said ledges and flange, gas burners laterally disposed with respect to said burner box, and burner tops over said burners resting freely upon said ledges and said flange. 60

5. A range comprising front, rear and side walls, the front and side walls having their top edge portions forming tubular borders, said borders and the top of said rear wall being provided with supporting ledges, and a range top resting freely upon said ledges. 65

LAWRENCE A. ALTHOFF.
